WINDING MACHINE

James E. Auten, West Barrington, R. I., assignor
to Universal Winding Company, Boston, Mass.,
a corporation of Massachusetts

Application February 18, 1935, Serial No. 7,100

12 Claims. (CL 74—217)

This invention relates to winding machines for winding cops, cones, cheeses and other forms of packages of thread, yarn, cord and similar strand material, hereinafter referred to generally by the term "yarn"; and particularly to winding machines wherein the package is rotated by contact with a drive-roll or drum. Specifically, the invention consists of a ribbon-breaker, so-called, which operates to control the disposition of the turns or coils of yarn on the surface of the winding to prevent the formation of bands or "ribbons" in which the coils are crowded together or "piled".

One object of the invention is to provide a simplified mechanism incorporated in the driving means of the winding machine and operating to disrupt the synchronism between the rotation of the package and the traverse of the yarn during the winding.

Another object of the invention is to provide a mechanism of the type indicated for periodically varying the speed ratio between the rotation of the package and the traverse of the yarn-guiding means at recurring cycles throughout the winding.

Another object of the invention is to provide a machine of the type indicated with mechanism driven from a constant speed source which is operable to intermittently change the ratio between the constant speed source and either the package-rotating means or the yarn-traversing means.

Another object of the present invention is to provide a winding machine of the type indicated having an expandible and contractible belt-driven pulley in the driving mechanism which is intermittently and positively actuated into contracted relationship to vary the diameter of its periphery engaged by the belt.

Another object of the invention is to provide a mechanism of the type indicated which is completely automatic in its operation and adjustable to meet all requirements.

Further objects of the invention are indicated in the following specification which describes a preferred form of construction of the device, by way of example, as illustrated by the accompanying drawings. In the drawings:

Fig. 1 is a side elevational view of a winding machine incorporating the novel features of the present invention and showing the driving mechanism and the winding elements of one unit of the machine;

Fig. 2 is an end elevational view of the machine illustrated in Fig. 1 showing the driving

belt connecting the expandible pulley with the source of power;

Fig. 3 is a view similar to Fig. 2 showing the expandible pulley partly in section to illustrate the manner in which the driving belt engages its periphery at a point nearer its axis;

Fig. 4 is a longitudinal sectional view of the expandible pulley and its operating means taken on line 4—4 of Fig. 2 and showing the sections of the pulley in closed relationship;

Fig. 5 is a sectional view similar to Fig. 4 taken on line 5—5 of Fig. 3 and showing the sections of the pulley in open relationship;

Fig. 6 is a part-sectional view of the expandible pulley and its operating means taken on line 6—6 of Fig. 4; and

Fig. 7 is a sectional view of the actuating cam for the pulley-operating arm taken on line 7—7 of Fig. 5 and showing the range of movement imparted to the follower-roller to actuate the arm.

The present invention relates generally to means for causing acceleration and deceleration in the speed of one of the winding elements of the machine, for example, the drive-roll for rotating the package; or, in other instances, it may be applied to the drive for the yarn-traversing means when the latter is operated independently of the drive-roll.

More specifically the invention relates to a driving mechanism between the prime-mover and the package-rotating means including a belt-driven expandible and contractible pulley which is automatically operated to vary the diameter of the periphery engaged by the belt. The invention also provides an intermittently operating means actuated from the driving mechanism and directly engaging the expandible and contractible pulley to positively actuate the latter to alter its diameter engaged by the belt whereby to vary the speed ratio between its constant speed source and the package-rotating means.

Referring to the drawings, the winding machine herein illustrated by way of example is of the double gang type comprising a plurality of winding units arranged in series along the opposite sides of a horizontal frame or bed 2 which is supported at its ends by legs 3. Spaced along the top of the bed 2 are a series of brackets 4 which mount bearings for the driving shafts and other parts of the winding mechanisms, two opposite units being located between each pair of brackets but only one unit being herein shown.

In the construction of the machine as shown

in Fig. 1 the winding mechanism of each unit comprises only two principal elements, namely: the winding-mandrel or spindle 15 on which the yarn-receiver or cop-tube C is rotatably supported; and the drive-roll 10 for rotating the yarn-receiver and in which is embodied the means for traversing the yarn back and forth axially of the package being wound. In this form of construction the usual reciprocating thread-guide is dispensed with, the drive-roll having its peripheral surface provided with a helical groove or grooves 8 and 9 extending in opposite directions and adapted to receive the strand of yarn to guide it back and forth between the ends of the package. This particular form of traversing means is shown and described in U. S. Letters Patent No. 1,749,355, dated March 4, 1930. It is to be understood, however, that the present ribbon-breaker or speed-changing device is adapted for use on winding machines of other types, for example, those wherein the package is driven by contact with a drive-roll and the yarn traversed by means of a reciprocating guide or with any other arrangement of drum-driven winders.

In the form of construction shown in Fig. 1 the drive-rolls 10 are mounted on and rotated by a horizontal shaft 11 journaled in ball bearings 12 on the bracket 4; the shaft 11 being extended throughout the whole length of the gang machine 30 to carry the drive-rolls for any desired number of winding units. A second parallel shaft 13, also journaled in bearings on the bracket 4, carries the drive-rolls, not herein shown, for the other series of winding units arranged on the opposite side of the winding frame or at the right-hand side as viewed in Fig. 2.

The present machine is shown as adapted for winding packages of conical form with the yarn built up on a suitable axial core or receiver, a wooden or fiber conical cop-tube C being illustrated in Fig. 1 as mounted to rotate on the winding-spindle or mandrel 15. The winding-spindle 15 is of usual construction and mounted in the manner illustrated in the patent referred to above. Suffice it to state herein that the winding-spindle 15 is swiveled to the forward end of a weighted arm 16 which is pivotally supported at its rearward end to adapt the surface of the yarn-receiver C, and of the package P, to be held in contact with the periphery of the drive-roll 10. As the yarn is built up on the cop-tube C it forces the latter upwardly with the arm 16 swinging on its pivot in the manner common to machines of the present type. Although not herein shown, a suitable stopping mechanism is usually employed with each unit of the machine to automatically arrest the winding operation by raising the package away from the drive-roll 10.

The driving transmission for the drive-roll shafts is similar to that shown and described in my copending application, Serial No. 741,012, filed August 22, 1934, and is therefore described but briefly herein. Bolted to the top of the bed 2 are a pair of spaced brackets or cross-frames 20 and 21 for supporting the ends of the drive-roll shafts 11 and 13 and the driving transmission therefor. The drive-roll shaft 11 projects beyond the bearing 12 in the bracket 4 with its reduced extremity 22 journaled in a ball bearing 25 on the frame 20, as indicated generally in Fig. 1. A belt-pulley 30 is keyed at 28 to the reduced end 22 of the shaft 11 and held against axial movement by a nut 29. The periphery of the pulley 30 is provided with a V-shaped groove 27 for receiving a driving belt as later described.

The opposite drive-roll shaft 13 is somewhat longer than the shaft 11 with its reduced end projecting through a clearance opening in the frame member 20 and journaled in a ball bearing 32 in the frame member 21. Mounted fast on the reduced end of the shaft 13 is a pulley 35 of the same form and size as the pulley 30 previously described. The pulley 35 is suitably keyed to the shaft 13 and held against axial movement by a nut 31, as shown in Fig. 2.

Arranged for vertical adjustment on the facing sides of the cross-frames 20 and 21 are two complementary brackets 37 and 38 received in grooves or guideways on the frames and held in adjusted position by means of disks 40 eccentrically mounted on a stud-shaft 42, see Fig. 2. The ends 41 of the shaft 42 project through bearing apertures in the cross-frames 20 and 21 with nuts 43 screwed onto their threaded extremities and set up against the sides of the frames to hold the shaft from turning. The peripheries of the eccentric disks 40 engage the opposite sides of horizontal slots 45 formed in the brackets 37 and 38 as shown in Fig. 2.

An enclosing housing or cradle 50 mounted between the cross-frames 20 and 21 carries the driving transmission for the drive-shafts 11 and 13. The housing 50 is suspended between the brackets 37 and 38 on a rock-shaft 52 passing through bearing sleeves 53 and 54 in the end walls and extending into bearing apertures 55 and 56 in the brackets. The rearward end 57 of the rock-shaft 52 extends beyond the cross-frame 21 as shown in Fig. 1 for connection with the means for actuating the speed-changing mechanism on the driving shaft to be later described.

The housing 50 is prevented from movement about the rock-shaft 52 by arms 58 and 59 engaging the sides of the housing. The arms 58 and 59 are slidably mounted on the machine bed 40 at opposite sides of the housing 50 and are adjusted into engagement with the walls of the housing 50 by means of screws 60 and 61 carried in depending webs on the arms and engaging the sides of the bed. The arms 58 and 59 are held 45 against the top of the bed 2 by bolts 62 passing through slots in their ends, see Fig. 1. The housing 50 may be vertically adjusted to any desired position with respect to the cross-frames 20 and 21 by rotating the eccentric disks 40 on 50 the stud-shaft 42.

A pair of driving shafts 64 and 65 are journaled in bearings in the housing 50 in spaced parallel relation below the rock-shaft 52. As shown in Fig. 1, the drive-shaft 64 is journaled in bearings 55 66 and 67 on the opposite end walls of the housing 50 with its forward end extending beyond the housing to receive a pulley 68 keyed thereto and held axially positioned thereon by a nut 70. The periphery of the pulley 68 is provided with a V-shaped groove in alignment with the groove 27 on the pulley 30, previously mentioned, and the two pulleys are connected by an endless belt 71 extending therebetween. The opposite end of the shaft 64 terminates in the bearing 67 in the 65 end wall of the housing 50, and adjacent the bearing a spur-gear 72 is fixed on the shaft. The shaft 64 is also provided with a worm 73 intermediate its ends and within the housing 50.

The shaft 65 is similarly journaled in suitable 70 bearings in the end walls of the housing 50 with its rearward end extending outwardly from the housing to receive a driven expandable pulley 75, hereinafter more fully described, and a driving sheave-type pulley 76 keyed to the shaft and 75

held in axial position by a nut 77. The pulley 76 is alined with the pulley 35 on the shaft 13 and the two pulleys are connected by a V-shaped belt 78. Within the housing 50 is a spur-gear 79 fixedly mounted on the shaft 65 for rotation therewith and intermeshing with the gear 72 on the shaft 64 to connect the two shafts to be driven together.

A cam-shaft 80 is suitably journaled in bearings 81 and 82 in the side walls of the housing 50 and is provided with a suitable worm-wheel or gear 83 engaging the worm 13 on the driving shaft 64. A cam 86 fixed to the shaft 80 intermediate its ends has a helical groove 87 for engaging a follower-roller 88 on a rocker-arm 89 fixedly connected to the rock-shaft 52. As most clearly shown in Fig. 1, the rocker-arm 89 depends from a hub 90 keyed to the shaft 52 and held against axial movement by a set-screw 91. With the construction described the cam-shaft 80 is rotated at a reduced speed from the driving shaft 64 to cause the cam 86 to oscillate the rock-shaft 52 by the engagement of its groove 87 with the roll 88 on the rocker-arm 89. The rock-shaft 52 may be continuously rocked between its extreme alternate positions or may be intermittently actuated in accordance with the contour of the cam-groove 87 which may be varied from the form shown in the drawings.

An electric motor 95 for driving the shaft 65 is mounted on a suitable pedestal 96 adjustably supported from a base 97 by means of studs 98 and adjusting nuts 99. The motor 95 is positioned below the bed at the rearward or right-hand end of the winding machine, as viewed in Fig. 2, and in driving relation to the shaft 65. Mounted on the armature-shaft 100 of the motor 95 is a driving pulley 101 disposed in alinement with the pulley 75, the two pulleys being connected by a V-shaped belt 102.

As before stated, the present invention provides a ribbon-breaker, so-called, for preventing ribboning of the yarn while winding by intermittently varying the speed of the driving shaft 45 to cause a slippage between the package and drive-roll and a change in the ratio of package-peripheral speed to traverse thereon, or, in other words, to interrupt the synchronism between the rotation of the package and the traverse of the 50 yarn. Broadly, the invention contemplates periodically altering the speed ratio of the driving and driven pulleys on the motor and driving shaft, respectively, by mechanically actuating and positively altering the effective diameter of 55 the periphery of the driven pulley engaged by the driving belt.

Referring now to Figs. 4 and 5, the pulley 75 is shown in the form of a sheave having a groove for receiving a V-belt and comprised of cooperating sections 105 and 106 which are relatively displaceable to vary the width of the groove so that the belt may engage the pulley at peripheries of different diameters. In the preferred form illustrated, the section 105 comprises a cylindrical sleeve or hub 107 having a radially extending flange 108 integral therewith and fixed with respect to the element 106. The pulley-section 105 is keyed to the shaft 65 at 109 and held against axial movement at one end by an oil-retaining ring 110 abutting the end of the bearing 67 in the housing 50; and by the abutting hub 111 on the pulley 76 at the other end. The inner face of the flange 108 has a plane surface 112 extending outwardly from the hub 107 with 75 a conical surface 113 adjacent the periphery of

the flange to form one-half of the V-shaped groove.

The pulley-section 106 is adapted for lateral movement with respect to the section 105, being formed with a hub 115 embracing the cylindrical sleeve 107 and an integral flange 116 having a plane surface 117 and an outer conical surface 118 for cooperation with the flange 108 to form the groove for receiving a V-shaped belt. The laterally movable section 106 is slidably mounted on the cylindrical sleeve 107 of the section 105 but is prevented from rotation relatively thereof by a key 120 engaging a keyway formed in the two elements. The section 106 is adapted to be engaged and laterally moved with respect to the section 105 and for this purpose a bearing flange 121 is mounted on the hub 115. To prevent excessive wear a ball-bearing 122 is provided between the bearing flange 121 and the hub 115. The inner race 119 of the bearing 122 is fitted to an annular shouldered seat on the hub 115 and held in place by a nut 125 screwed on the threaded end of the hub; while the outer race 120 is forced into a recess in the offset hub of the flange. When in its assembled relationship, as shown in Figs. 4 and 5, the bearing flange 121 is spaced from the outer face of the flange 116 of the pulley-section 106 so that the latter may be rotated independently of the flange 121.

The pulley-section 106 is positively moved axially with respect to the section 105 from the position shown in Fig. 5 to that shown in Fig. 4 by an oscillating lever 125 which directly engages the bearing flange 121. The lever 125 comprises a pivoted hub portion 126 having a depending bifurcated shifting fork 127 and an upwardly projecting follower-arm 128. The lever 125 is rockably mounted on a pin 129 extending through a bearing in its hub 126 with its ends fixedly held in depending webs 131 on the bracket 38. As more clearly shown in Fig. 6, the bifurcated shifting fork 127 comprises arms 132 and 133 of semicircular shape extending from the hub 126 to straddle the sides of the hub of the bearing flange 121. The arms 132 and 133 terminate in rounded extremities 134 for engaging the flange 121 on opposite sides of the shaft 65. The follower-arm 128 of the lever 125 is provided with a bearing roller 135 fixed to the end of the arm by means of a stud 136. The lever 125 is periodically rocked by the engagement of the bearing roller 135 with an oscillating cam 140.

The cam 140 is constructed in the form of a collar 141 fixed to the extension 57 of the rock-shaft 52, previously mentioned, by means of set-screws 142 and having a depending arm 143 extending inwardly with a beveled face 144 at its end adapted to engage the convex periphery of the roller 135 on the lever 125. The end face 144 of the arm 143 is inclined at an angle to the pivotal axis of the lever 125 to form a cam slidably engaging the roller 135 to move it between the positions indicated at *a* and *b* in Fig. 7 as the rock-shaft 52 oscillates from one extreme position to the other. This motion of the roller 135 is transmitted through the lever 125 to cause its fork 127 to axially shift the pulley-section 106 relatively of the fixed section 105.

Having now described the construction and arrangement of the various parts of the mechanism of the winding machine the mode of operation of the ribbon-breaker will next be explained. Referring to Fig. 1 of the drawings, the machine is prepared for winding by mounting a suitable

wooden or fiber cone-tube or yarn-receiver C to rotate on the spindle 15. For this purpose the arm 16 is raised on its pivot and the spindle 15 swung outwardly on its swiveled joint at the outer end of the arm in accordance with the usual practice. After the cop-tube C is in place the spindle 15 is swung back into position above the drive-roll 10 and the arm 16 lowered to bring the surface of the tube into driving contact with the periphery of the roll. The strand of yarn y or other material is led up from its source of supply through a tension-device, not herein illustrated, thence drawn across the periphery of the drive-roll 10 and its end attached to the cop-tube C 15 in any suitable manner.

The housing 50 carrying the driving transmission is adjusted vertically to properly tension the belts 71 and 78 by loosening the nuts 43 on the ends of the stud-shaft 42, which allows the entire assembly of housing 50, rock-shaft 52 and brackets 37 and 38 to move downwardly. The weight of the assembly is such as to properly tension the belts by adjusting the housing 50 to its operative position on the rock-shaft 52. The nuts 43 are then tightened in position and the arms 58 and 59 adjusted by means of the screws 60 and 61 to engage and rigidly hold the housing against lateral movement.

The operation of the machine is started by closing a circuit breaker or switch (not herein shown) to energize the motor windings from a source of current. The motor 95 drives the shaft 65 in a counterclockwise direction through its belt connection with the expandable pulley 75 and the shaft 64, in turn, is driven by the intermeshing gears 72 and 79 in a clockwise direction. The shaft 11 carrying the drive-rolls 10 on one side of the machine is driven from the shaft 64 in a clockwise direction by the belt 71 connecting the pulleys 68 and 30 at the forward end of the housing, as viewed in Fig. 1.

Also, on the opposite side of the machine, as more clearly shown in Fig. 2, the shaft 13 carrying a similar series of drive-rolls is driven directly from the driving shaft 65 through the belt 78 connecting the pulleys 76 and 35. From the above explanation it will be apparent that the two series of drive-rolls 10 on opposite sides of the machine are driven by the motor in opposite directions of rotation to wind packages from yarn supplied thereto in the usual manner.

As all the winding units function in the same manner it will be sufficient to explain the method of operation of one of them. The drive-roll 10 is driven continuously and as the cop-tube C makes contact with its periphery it is rotated by the roll to wind on the yarn. As the yarn is taken up by the rotation of the cop-tube C the strand y enters the helical groove or grooves 8 and 9 on the periphery of the roll 10 to be traversed thereby to deposit it on the receiver in helical coils which make several turns first in one direction and then in the opposite direction. In this way the yarn is given a continuous traverse from one end of the cop-tube to the other and back again to build up a succession of courses forming overlying layers which constitute the yarn body of package.

At the start of the winding the rotative speed of the cop-tube C will have a certain ratio to that of the drive-roll 10 depending upon their respective diameters and the yarn will be laid from end to end of the tube with a corresponding ratio in the number of coils to the number 75 of turns in the groove or grooves 8 and 9. As

the yarn builds up on the cop-tube C the latter recedes from the drive-roll 10 and with the increase in diameter of the yarn mass its angular velocity or speed of rotation is gradually lessened, due to the increasing disparity between its diameter and that of the drive-roll. In other words, there is a constant change in ratio between the rotative speed of the package and drive-roll and, consequently, there will be a corresponding variation in the number of turns laid on the surface of the package, or in the "wind" as it is called.

At the start of the winding the yarn coils may be laid in "open" or spaced relationship, but when the "wind" changes the spacing between the turns is lessened and the coils gradually close up and eventually tend to crowd together in bands or "ribbons". This crowding or piling of the yarn coils takes place each time the wind changes from a greater to a lesser number of even turns and ordinarily causes a "ribbon wind" on the surface of the package. When several coils are laid over each other in the "ribbon" they tend to slip and slide out of place and roll on the surface of the package. This disturbs the twist of the yarn and tends to weaken it so that its quality is impaired and, as another serious defect, the "ribbon" prevents the yarn from delivering freely when it is drawn off over the end of the package. The present invention operates to overcome this defect of "ribbon wind" in drum-wound packages by periodically varying the ratio between the rotation of the package and the traverse of the yarn to disrupt the synchronism thereof.

To this end the driving shaft 64 operates through the worm 73 and worm-wheel 83 to rotate the cam 86 whereby to oscillate the rock-shaft 52 from its follower arm connection with the cam-groove 87. As the rock-shaft extension 51 and its depending cam 140 oscillates from its extreme forward to extreme rearward positions the lever 125 is rocked in a plane at right-angles to the plane of movement of the cam through the engagement of the roller 135 with the cam-face 144. Due to the pivotal mounting of the lever 125 intermediate its ends and the direct engagement of its shifting fork 127 with the bearing flange 121 on the movable section 106 of the expandable pulley 75, the oscillatory movement of the rock-shaft 52 is converted into a positively-actuated sliding movement of the pulley-section 106 to shift it toward the section 105.

When the cam 140 on the rock-shaft extension 51 is moved to the extreme position shown in full lines in Fig. 7, the pulley-section 106 is moved to its closed position by the direct engagement of the extremities 134 of the shifting fork 127 with the bearing flange 121 as shown in Figs. 2 and 4. With the sections of the pulley 75 closed together in this manner the diameter of its periphery engaged by the belt 102 is at a maximum and, since the diameter of the pulley 101 on the driving motor shaft remains constant, the ratio of the driving and driven elements is such that the driving shaft 65 of the winding machine will be driven at its slowest rate of speed. With the pulley-sections closed together in this relationship the belt is tensioned on both sides as shown in Fig. 2.

As the driving mechanism continues its operation the rock-shaft extension 51 rocks the cam 140 to its opposite extreme position as shown in dotted lines in Fig. 7, thereby releasing the lever 125 to permit the section 106 of the pulley 75 to

be moved laterally away from the section 105 to separate its face 118 from the face 113. Due to the beveled or conical contour of the faces 113 and 118 on the two sections 105 and 106 of the pulley 75 the tension of the belt 102 will cause the section 106 to be wedged away from the section 105 under the control of the lever 125 so that the belt will ride deeper into the groove between the two pulley-sections or, in other words, the belt will engage the pulley at a lesser circumference on its periphery. The engagement of the roller 135 on the lever 125 with the cam-face 144 and the engagement of the shifting fork 127 with the bearing plate 121 positively control the lateral movement of the section 106 in varying the diameter of the pulley 75 engaged by the belt 102. In other words, the movement of the lever 125 and thereby the movement of the pulley-section 106 is positively controlled by the cam-face 144. As the sections 105 and 106 of the pulley 75 are moved apart or opened while the diameter of the driving pulley on the motor remains constant, the speed ratio between the motor shaft and the driving shaft 65 is varied until with the parts in the position shown in Figs. 3 and 5, the driving shaft 65 will be driven at a maximum rate of speed. The tension of the driving belt 102 on the pulley 75 is maintained substantially constant due to centrifugal force which throws the belt outwardly on its relatively slack side, as shown in Fig. 3, and insures engagement with the pulley at the deepest possible position in the groove. This action of centrifugal force on the belt is due to its linear velocity and change of direction in passing over the pulley as well understood in the art.

The constant change or periodic acceleration and deceleration in the speed of the driving shaft 65 is transmitted to both of the drive-roll shafts 11 and 13 and the variation in the speed of the drive-rolls has the effect to periodically vary the rate of traverse of the yarn following the helical grooves on the rolls. On the other hand, due to the momentum and inertia of the package during deceleration and acceleration of the drive-roll, respectively, the package will slip or "skid" on the periphery of the roll and, as a result thereof, the synchrony of winding speed to yarn traverse is disrupted at frequent intervals to prevent ribbons winding. The rock-shaft 52 is oscillated through its connection with the shaft 64 at a greatly reduced rate of speed and in the embodiment of the invention herein illustrated it is continuously rocked between extreme positions. If desired, however, the rate at which the rock-shaft 52 is actuated may be varied over a considerable range and the form of the cam 86 may be changed from that illustrated to transmit a different periodic motion to the rock-shaft. It has been demonstrated that if the rock-shaft is continuously operated at the rate of forty cycles per minute while the driving shaft 65 rotates the drive-rolls 10 to wind 720 yards of yarn per minute "ribbon winding" will be prevented. It is to be understood, however, that the rate of cyclic change in the speed of the driving elements is not critical and any suitable rate of change which prevents "ribbon winding" is intended to be included within the scope of the invention. It will be observed from the foregoing that the present invention provides means in a winding machine for preventing the formation of "ribbons" in the winding by positively varying the speed ratio between the driving and driven elements through the use of a laterally expandible

pulley directly actuated to positively control and vary the diameter of the periphery engaged by a belt.

It will also be apparent to one skilled in the art that the novel features of the present invention may have a variety of mechanical expressions other than those illustrated and described. Further, it will be apparent that the ribbon-breaker mechanism may be applied to other types of winding machines and that other forms of actuating mechanism directly engaging and positively actuating the laterally expandible pulley may be substituted for that herein shown. Therefore, without limiting myself in this respect, I claim:

1. In a winding machine, a driving motor, a driving shaft, sheave-type pulleys on said motor shaft, a belt connecting the pulleys, one of said pulleys comprising laterally adjustable sections, means directly engaging one of the sections of the pulley to move it laterally with respect to the other section, means for intermittently actuating the adjusting means to cause the belt to engage the pulley at different diameters on its periphery to vary the speed of the driving shaft, and means for continuously operating said actuating means.

2. In a winding machine, a driving motor, a driving shaft, a sectional pulley on the driving shaft having one of its sections axially movable, a belt connecting the motor and pulley, a shifting fork engaging the movable section of the pulley, an oscillating cam for actuating the shifting fork to intermittently alter the diameter of the pulley engaged by the belt whereby to vary the speed of the driving shaft, and means for oscillating the cam.

3. In a winding machine, a driving motor, a driving shaft, a rock-shaft operatively connected with the driving shaft, a sectional pulley on the driving shaft having one section axially movable, a belt connecting the motor and the pulley on the driving shaft, a pivoted lever having a shifting fork engaging the movable section of the pulley, a cam on the rock-shaft for actuating the lever to intermittently alter the diameter of the periphery of the pulley engaged by the belt to vary the speed of the driving shaft, and means for actuating the cam.

4. In a winding machine, a driving shaft, an expandible pulley on the driving shaft for varying its rotative speed comprising a section fixed to the shaft and a cooperating section slidably mounted on the shaft, means for engaging and positively actuating the movable section of the pulley, and means for intermittently operating said actuating means.

5. In a winding machine, a driving shaft, an expandible pulley on the driving shaft for varying its rotative speed comprising a section fixed to the shaft and a cooperating section slidably mounted on the shaft, a shifting fork for actuating the sliding section, and means actuated by the driving shaft for moving the shifting fork to actuate the sliding section to vary the effective diameter of the pulley.

6. In a winding machine, a driving shaft, a sectional expandible pulley on the driving shaft having one section movable for varying the rotative speed of the driving shaft, a shifting fork engaging the movable section of the pulley, a rock-shaft driven by the driving shaft, a cam on the rock-shaft engaging the shifting fork to intermittently actuate the movable section to

- close the pulley to alter its effective diameter, and means for actuating the cam.
7. In a winding machine, a driving shaft, a driven shaft, said shafts being journaled to rotate about fixed axes, pulleys on said shafts, a belt connecting the pulleys, one of said pulleys being expansible to alter the diameter of its periphery engaged by the belt, mechanical means operating on the expansible pulley to positively 10 alter the diameter of its periphery engaged by the belt, and means for intermittently actuating the pulley-operating means to alternately increase and decrease the speed of the shaft driven by the pulley.
- 15 8. In a winding machine, a driving shaft, a driven shaft, said shafts being journaled to rotate about fixed axes, pulleys on said shafts, a belt connecting the pulleys, one of said pulleys being expansible to alter the diameter of its periphery engaged by the belt, mechanical means 20 engaging the pulley and operating to positively alter the diameter of its periphery, and means operated from one of the shafts for positively actuating the pulley-engaging means to alternately increase and decrease the speed of the shaft driven by the pulley.
- 25 9. In a winding machine, a driving shaft, a driven shaft, said shafts being journaled to rotate about fixed axes, sheaf-type pulleys on said shafts, a belt connecting the pulleys, one of said pulleys comprising laterally adjustable sections, mechanical means for positively moving one of the sections of the pulley with respect to the other to alter the diameter of the periphery of the pulley engaged by the belt, and means for intermittently actuating the pulley-operating means
- 30 to alternately increase and decrease the speed of the shaft driven by the pulley.
- 10 10. In a winding machine of the type in which a package is rotated and the yarn traversed axially thereof, the combination of an expansible pulley for driving the package, a driving belt on said pulley, mechanical actuating means operating on said pulley to positively alter the diameter of the pulley engaged by the belt, and means for intermittently operating the actuating means to periodically alter the speed of the pulley.
- 15 11. In a winding machine of the type in which a grooved drive-roll rotates a package by peripheral contact therewith and traverses the yarn longitudinally thereon, the combination of an expansible pulley for driving the package, a driving belt on said pulley, mechanical actuating means operating on the pulley to positively alter the diameter of its periphery engaged by the belt, and means for intermittently operating the actuating means to periodically alter the speed of the expansible pulley.
- 20 12. In a winding machine of the type in which two series of yarn packages are arranged in spaced parallel relationship and driven by peripheral contact with a series of drive-rolls while the yarn is traversed longitudinally thereof, the combination of a pulley for driving the two series of drive-rolls, said pulley having a movable element for altering the diameter of its periphery engaged by the belt, a driving belt on said pulley, mechanical actuating means operating on the movable element of the pulley to positively alter the diameter of its periphery, and means for intermittently operating the pulley-actuating means to periodically alter the speed of the pulley.

JAMES E. AUTEN.

CERTIFICATE OF CORRECTION.

Patent No. 2,091,902.

August 31, 1937.

JAMES E. AUTEN.

It is hereby certified that error appears in the printed specification of the above numbered patent requiring correction as follows: Page 5, second column, line 18, claim 1, before the word "shaft" insert and; and that the said Letters Patent should be read with this correction therein that the same may conform to the record of the case in the Patent Office.

Signed and sealed this 19th day of October, A. D. 1937.

(Seal)

Henry Van Arsdale.
Acting Commissioner of Patents.

- close the pulley to alter its effective diameter, and means for actuating the cam.
7. In a winding machine, a driving shaft, a driven shaft, said shafts being journaled to rotate about fixed axes, pulleys on said shafts, a belt connecting the pulleys, one of said pulleys being expansible to alter the diameter of its periphery engaged by the belt, mechanical means operating on the expansible pulley to positively 10 alter the diameter of its periphery engaged by the belt, and means for intermittently actuating the pulley-operating means to alternately increase and decrease the speed of the shaft driven by the pulley.
- 15 8. In a winding machine, a driving shaft, a driven shaft, said shafts being journaled to rotate about fixed axes, pulleys on said shafts, a belt connecting the pulleys, one of said pulleys being expansible to alter the diameter of its periphery engaged by the belt, mechanical means 20 engaging the pulley and operating to positively alter the diameter of its periphery, and means operated from one of the shafts for positively actuating the pulley-engaging means to alternately increase and decrease the speed of the shaft driven by the pulley.
- 25 9. In a winding machine, a driving shaft, a driven shaft, said shafts being journaled to rotate about fixed axes, sheaf-type pulleys on said shafts, a belt connecting the pulleys, one of said pulleys comprising laterally adjustable sections, mechanical means for positively moving one of the sections of the pulley with respect to the other to alter the diameter of the periphery of the pulley engaged by the belt, and means for intermittently actuating the pulley-operating means
- 30 to alternately increase and decrease the speed of the shaft driven by the pulley.
- 10 10. In a winding machine of the type in which a package is rotated and the yarn traversed axially thereof, the combination of an expansible pulley for driving the package, a driving belt on said pulley, mechanical actuating means operating on said pulley to positively alter the diameter of the pulley engaged by the belt, and means for intermittently operating the actuating means to periodically alter the speed of the pulley.
- 15 11. In a winding machine of the type in which a grooved drive-roll rotates a package by peripheral contact therewith and traverses the yarn longitudinally thereon, the combination of an expansible pulley for driving the package, a driving belt on said pulley, mechanical actuating means operating on the pulley to positively alter the diameter of its periphery engaged by the belt, and means for intermittently operating the actuating means to periodically alter the speed of the expansible pulley.
- 20 12. In a winding machine of the type in which two series of yarn packages are arranged in spaced parallel relationship and driven by peripheral contact with a series of drive-rolls while the yarn is traversed longitudinally thereof, the combination of a pulley for driving the two series of drive-rolls, said pulley having a movable element for altering the diameter of its periphery engaged by the belt, a driving belt on said pulley, mechanical actuating means operating on the movable element of the pulley to positively alter the diameter of its periphery, and means for intermittently operating the pulley-actuating means to periodically alter the speed of the pulley.
